UNITED STATES PATENT OFFICE.

A. M. SAFFORD, OF SPRINGFIELD, MASSACHUSETTS.

IMPROVEMENT IN HERBALS AND SCRAP-BOOKS.

Specification forming part of Letters Patent No. 43,135, dated June 14, 1864.

To all whom it may concern:

Be it known that I, A. M. SAFFORD, of Springfield, in the county of Hampden and State of Massachusetts, have invented an Improved Herbarium; and I do hereby declare that the following is a full and exact description thereof, reference being had to the accompanying drawings, making part of this specification.

Figure 1 is a view in perspective of a herbarium open constructed in my improved manner; Fig. 2, a transverse section of the same.

Like letters designate corresponding parts in both figures.

Each sheet or leaf B of the herbarium is made of thick binder's board, thin pieces of wood, or equivalent material, of the size desired, and as thick as any of the specimens of plants to be preserved may require, and be contained within the planes of its surfaces, when inserted in openings of the board. These sheets are cut away, except a sufficient margin or border, b, all round, so as to leave all the middle portion, a, open to receive the plants in. Then on one side of the sheet or frame thus formed is stretched a strong, thick sheet of smooth paper, c, forming a back thereto. The space a thereby becomes a shallow box, which is to hold the plant; and the plant is to be secured to the back c by glue, thread, or any other convenient means in the usual manner. The sheets or boards B may be of various thicknesses, as different specimens may require, so that they may sink flush with or beneath the sides b b. As many

of these sheets as it may be desired to have together are bound in a cover, A, in the manner of an ordinary book or album, substantially as shown in the drawings, and when folded together the sheets will all shut close to one another, so as to completely inclose the specimens and protect them from the air and from insects and other vermin, and the whole makes a neat appearance. They are as readily examined as a picture or the contents of a book. The genus and species of a plant, and any other particulars, such as are ordinarily written in herbariums, may be written either on the same side of the back c as where the plants are attached, as indicated at f, Fig. 1, or on the back of the same sheet, or on the back of the sheet preceding, so as to be seen in the same folio or opening as the plant.

An herbarium book or sheets of this kind also may be useful for attaching small pictures, drawings, scraps, &c., instead of a scrap-book, and be much neater in appearance than ordinary scrap-books, since the book shuts the leaves close, and thus keeps in good shape.

What I claim as my invention, and desire to secure by Letters Patent, is—

The improved herbarium constructed and arranged substantially as herein specified.

The above specification of my improved herbarium and scrap-book signed by me this 22d day of March, 1864.

A. M. SAFFORD.
